W. L. EWING

COMBINED ADVERTISING CIGAR CUTTER AND LIGHTER STAND

Filed April 13, 1927

Walter L. Ewing, INVENTOR
BY Victor J. Evans
ATTORNEY

UNITED STATES PATENT OFFICE.

WALTER L. EWING, OF PHILADELPHIA, PENNSYLVANIA.

DESIGN FOR A COMBINED ADVERTISING CIGAR CUTTER AND LIGHTER STAND.

Application filed April 13, 1927. Serial No. 21,581. Term of patent 3½ years.

To all whom it may concern:

Be it known that WALTER L. EWING, a citizen of the United States, residing at Philadelphia, in the county of Philadelphia and State of Pennsylvania, has invented a new, original, and ornamental Design for a Combined Advertising Cigar Cutter and Lighter Stand, of which the following is a specification, reference being had to the accompanying drawings, forming a part thereof, and wherein there is illustrated a single perspective view of a combined advertising cigar cutter and lighter stand showing the new design.

What is claimed is:

The ornamental design for a combined advertising cigar cutter and lighter stand, as shown.

WALTER L. EWING.
